UNITED STATES PATENT OFFICE.

ERICK WALDEMAR LINDGREN, OF STOCKHOLM, SWEDEN.

APPARATUS FOR AUTOMATIC DELIVERY OF FLUIDS OR OTHER GOODS.

SPECIFICATION forming part of Letters Patent No. 767,903, dated August 16, 1904.

Application filed October 2, 1903. Serial No. 175,497. (No model.)

To all whom it may concern:

Be it known that I, ERICK WALDEMAR LINDGREN, ironmonger, a subject of the King of Sweden, residing at Järfvavägen 6, Hagalund, 5 Stockholm, Sweden, have invented certain new and useful Improvements in Apparatus for the Automatic Delivery of Fluids or other Goods; and I do declare the following to be a full, clear, and exact description of the invention, 10 such as will enable others skilled in the art to which it appertains to make and use the same.

This invention relates to improvements in check-controlled apparatus for the vending of fluids or other goods, and more particularly 15 to that class of such apparatus in which a coin-check serves as a connector between the operating parts and the delivery mechanism.

The object of the invention is to improve and simplify the construction and operation 20 of machines of this character, and thereby render them more efficient and durable in use and less expensive to produce.

With this and other objects in view the invention consists of certain novel features of 25 construction, combination, and arrangement of parts, as will be more fully described, and particularly pointed out in the appended claims.

In the accompanying drawings, Figure 1 is 30 a top plan view of my improved check or coin-controlled apparatus adapted for operating a fluid-delivery mechanism. Fig. 2 is a similar view with the operating-lever and other parts omitted to more clearly illustrate the parts beneath them. Fig. 3 is a similar top plan view 35 of the base-plate of the machine with the coin-controlled parts omitted to more clearly illustrate the fluid-delivery mechanism. Fig. 4 is a detail vertical sectional view taken on the 40 line $\alpha\alpha$ of Fig. 1 and showing the coin way or passage. Fig. 5 is a top plan view, on an enlarged scale, of the operating-lever and the coin-controlled parts. Fig. 6 is an end elevation 45 of the parts shown in Fig. 5 in an inverted position.

Referring to the drawings more particularly, A denotes a horizontally-disposed base-plate or other portion of a suitable frame or support upon which my improved coin-controlled apparatus is mounted. Said plate A is

formed adjacent to its center with an opening or slot a and at its rear with a cut-away portion b , adjacent to which is secured a bracket c . Beneath said plate A, as shown in Fig. 3, is mounted a fluid-delivery valve or faucet d , 55 having a sliding valve-stem 21, which is opened by an outward or rearward sliding movement, as presently explained. Projecting vertically from the upper side of the plate A is a fixed stud or pivot 2^a , upon which is pivoted a hand-lever 28, having at its outer end a hand-piece 28^a and at its inner end a nose or projection 38. Said lever 28 is held to the left in its normal position by a coil-spring 28^b, as shown in Fig. 5. Pivoted also upon said pivot pin or 60 bolt 2^a , but below and independent of the lever 28, is a coin-locking member 2 in the form of an irregular-shaped plate, as clearly seen in Figs. 5 and 6. Said swinging or oscillating member or plate 2 is formed upon its upper side 65 with a raised or thickened portion 2^b , which is recessed to form an overhanging portion 33 and a space 3 beneath the latter. The under side of said member 2 is formed with a shoulder 27 and has a friction-roller 2^c journaled adjacent to one of its side edges. Said member 2 is held in its normal position, as shown in the several views of the drawings, by a coil-spring 11 70 and is only oscillated when it is locked or connected to the hand-lever 28 by a coin or check, 75 as hereinafter described. Pivoted at the rear of the upper side of the member or plate 2 upon a pin or screw 9^a is a swinging arm 9, which is pressed normally against the portions 2^b and 33 of the member 2 by a coil-spring 37. Said arm 9 is thus pivoted at one 80 of its ends, and to its opposite end is pivoted, by means of a pin or rivet 1^a, a swinging coin-engaging member 1, as clearly seen in Fig. 5 of the drawings. Said member 1 has a portion 1^b formed with a nose or projection 39, which lies normally in the path of the nose 38 on the lever 28, so that when the latter is 85 swung to the right the portion 1^b of the member 1 will be swung into the space 3 beneath the overhanging portion 33 of the member or plate 2, in which portion 33 is formed a vertically-disposed coin passage or way 4, as shown. The portion 1^b of the member 1 lies 90 normally under the outer edge of the portion 100

33, as seen in Fig. 5, but does not cover the coinway 4. Said member 1 is also formed at its rear end with a projection 34, which is connected to a similar projection 35 on the arm 9 by a coil-spring 36, which serves to hold said member in its normal position. Fixed upon the under side of the arm 9 is a depending pin or stud 5, which projects through a curved or cam slot 6, formed in the rear edge of the member or plate 2, and also through a similar slot 10^a, formed in the free end of a curved plate 10, pivoted at 10^b upon the under side of the member or plate 2, as indicated by the dotted lines in Fig. 2, and serving as a bottom 10 for the coin way or passage 4 to limit the downward movement of a coin or check 14, as shown in Fig. 4. The lower end of said pin 5 contacts with a curved or cam-shaped ledge 18, formed upon the upper face of a plate 17, which is pivoted at one of its ends, as at 16, upon the upper side of the base-plate A and which has its opposite end disposed beneath the rear or free end of the bottom plate 10, as seen in Fig. 2. Upon the upper side or face 15 of the rear or free end of said plate 17 are an upwardly-projecting lug 20 and a friction-roller 20^a, which lug and roller are engaged by an arm 7, secured to a shaft 8, which is journaled in the said bracket *c* upon the base-plate A. Upon said shaft 8 is a second arm 15, having a forked outer end 15^a, which engages and operates the stem 21 of the valve or faucet *d*. Also secured upon said shaft 8 is an arm or lever 22, the forward or free end 20^a of which is engaged by a catch or detent 26, pivoted at 26^b in a bracket secured to the base-plate A and actuated by a spring 26^c, as shown. The arm or lever 22 and also the arms 7 and 15, which are secured to the shaft 8, are actuated by a coil-spring 32, which has one of its ends attached to a stud 22^c upon the lever 22 and its other end secured to a similar stud 2^d upon the portion 33 of the member or plate 2, so that the tendency of the spring 32 45 is to move the arm 22 inwardly and hold it in contact with the detent 26 or the friction-roller 2^c and also to move the arms 7 and 15 rearwardly or outwardly, thereby opening the valve *d* and swinging the plate 17 rearwardly to cause its cam-ledge 18 to actuate the pin 5, the movement of which will swing the bottom plate 10 from beneath the coinway 4 to permit the coin 14 to drop through the slot *a* in plate A and fall into a suitable coin-box. (Not shown.) One end of the detent or dog 26, as previously stated, engages the end 22^a of the arm or lever 22, and its opposite end 26^c lies in the path of the said shoulder 27, which is provided upon the under side of the member 2 and is adapted to actuate said detent to disengage it from the arm or lever 22. The operation of the invention is as follows: When a check or coin 14 is deposited in the coin-passage 4, it falls upon the plate 10, 65 as seen in Fig. 4, and blocks the space 3 in

front of the portion 1^b of the coin-engaging member 1, so that when the lever 28 is swung to the right its nose 38 will engage the nose 39 and move the member 1 into engagement with the coin, which will thus serve as a connector and cause the coin-locking member 2 to oscillate with the lever 28 against the tension of the spring 11. As the member 2 is thus oscillated its shoulder 27 will engage the detent 26 and cause it to disengage the arm 22. The spring 32 will then swing the arm 22 inwardly until it contacts with the roller 2^c, and the movement of the arm 22 will, through the shaft 8, swing the arms 7 and 15 rearwardly. The rearward movement of the arm 15 will actuate the valve-stem 21 to open the valve *d* and permit of the discharge of a certain quantity of fluid, and the arm 7 in its rearward movement will engage the stud 20 and roller 20^a and cause the plate 17 to be swung rearwardly. In this movement of the plate 17 the pin 5 will ride over the cam-ledge 18 and be moved rearwardly to both swing the bottom plate 10 rearwardly to release the coin 14 and to swing the arm 9, and hence the member 1, rearwardly to permit the nose 38 of the lever to pass the nose 39 on said member 1. As soon as released the lever 28 and also the member 2 will return to their normal positions by reason of their springs 28^b and 11, and the return movement of the member 2 will force the arm 22 to its original position, in which it will be locked by the detent 26. The arms 7 and 15 and springs 36 and 37 will restore the other parts 100 of the apparatus to their normal positions, as will be readily understood. If the hand-lever 28 should be turned without previously depositing a coin in the coinway 4, it will be seen that portion 1^b of the coin-engaging member 1 will be swung into the space 3 without actuating the member 2. When the nose 38 passes the nose 39, the spring 36 will restore the member 1 to its normal position, and the nose 38 in the return movement of the lever 28 will be permitted to pass the nose 39, owing to the manner in which the member 1 is mounted.

While I have shown and described the preferred embodiment of my invention, I wish it understood that I do not limit myself to the precise construction herein set forth, since various changes in the form, proportion, and the minor details of construction may be resorted to without departing from the principle or sacrificing any of the advantages of this invention.

It will be further understood that the coin-controlled mechanism may be used for vending a merchantable commodity of any description instead of simply a fluid, as herein shown and described.

From the foregoing description, taken in connection with the accompanying drawings, the construction and operation of the inven- 130

tion will be readily understood without requiring a more extended explanation.

Having thus described my invention, what I claim as new, and desire to secure by Letters 5 Patent, is—

1. In an apparatus of the character described, the combination of a suitable support, a coin-locking member mounted to oscillate upon said support and having a coin-passage, a
- 10 swinging arm, mounted upon said coin-locking member, a coin-engaging member pivotally mounted upon said swinging arm and adapted to be locked to said coin-locking member by a coin deposited in said coin-passage,
- 15 an operating element for swinging said coin-engaging member, a delivery mechanism, and means controlled by said coin-locking member for actuating said delivery mechanism, substantially as described.
- 20 2. In an apparatus of the character described, the combination of a suitable support, a pivot upon said support, a spring-retracted coin-locking member mounted to swing upon said pivot and provided with a coin-passage, a
- 25 spring-retracted swinging arm pivotally mounted upon said coin-locking member, a spring-retracted coin-engaging member pivoted to said swinging arm and adapted to swing across said coin-passage and to be locked to
- 30 said coin-locking member by a coin deposited in said coin-passage, a spring-retracted operating-lever for actuating said coin-engaging member, a delivery mechanism, and means controlled by said coin-locking member for act- 35 tuating said delivery mechanism, substantially as described.
3. In an apparatus of the character described, the combination of a suitable support, a pivot upon said support, a spring-retracted coin- 40 locking member mounted to swing upon said pivot and provided with a coin-passage, a spring-retracted swinging arm pivotally mounted upon said coin-locking member, a spring-retracted coin-engaging member pivoted to said swinging arm and adapted to swing across said coin-passage and to be locked to
- 45 said coin-locking member by a coin deposited in said coin-passage, a spring-retracted operating-lever for actuating said coin-engaging member, a movable actuating element of a 50 delivery mechanism, and a bell-crank lever for imparting the movement of said coin-locking member to said actuating element of the delivery mechanism, substantially as described.
- 55 4. In an apparatus of the character described, the combination of a suitable support, a pivot upon said support, a spring-retracted coin-locking member mounted to swing upon said pivot and provided with a coin-passage, a
- 60 spring-retracted swinging arm pivotally mounted upon said coin-locking member, a

spring-retracted coin-engaging member pivoted to said swinging arm and adapted to swing across said coin-passage and to be locked to said coin-locking member by a coin deposited 65 in said coin-passage, a spring-retracted operating-lever for actuating said coin-engaging member, a movable actuating element of a delivery mechanism, a spring-operated bell-crank lever for operating said actuating element of the delivery mechanism, and a locking-detent for said bell-crank lever adapted to be actuated by said coin-locking member, substantially as described.

5. In an apparatus of the character described, 75 the combination of a suitable support, a pivot upon said support, a coin-locking member mounted upon said pivot and provided with an undercut portion having a coin-passage extending vertically through the same, a pivotally-mounted bottom plate adapted to close the lower end of said coin-passage, a coin-engaging member mounted to swing in said undercut portion across said coin-passage and adapted to be locked to said coin-locking member by the deposit of a coin in said coin-passage, means for operating said coin-engaging member, and means actuated by said coin-locking member for swinging said bottom plate from beneath said coin-passage in order to release the deposited coin, substantially as described.

6. In an apparatus of the character described, the combination of a suitable support, a pivot upon said support, a coin-locking member 95 mounted upon said pivot and provided with an undercut portion having a coin-passage extending vertically through the same, a pivotally-mounted bottom plate adapted to close the lower end of said coin-passage, a swinging 100 arm pivoted upon said coin-locking member and having a depending pin projecting into a slot in said bottom plate, a coin-engaging member pivoted upon said swinging arm and adapted to swing in said undercut portion across 105 said coin-passage and to be locked to said coin-locking member by the deposit of a coin in said coin-passage, a lever for operating said coin-engaging member, a bell-crank lever actuated by said coin-locking member, and a pivoted 110 plate actuated by said bell-crank lever and adapted to actuate said depending pin upon said swinging arm to move said bottom plate from under said coin-passage, substantially as described.

In testimony whereof I affix my signature in presence of two witnesses.

ERICK WALDEMAR LINDGREN.
